(57) **CLAIM**

The ornamental design for a bottle lid as shown and described.

DESCRIPTION

FIG. 1 is a front, right and top perspective view of a bottle lid in an open state, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the bottle lid of FIG. 1 in a closed state, shown in an environment of use.

The dashed broken lines depict portions of the bottle lid that form no part of the claimed design. The additional dashed broken lines in FIG. 9 depict environmental structure and form no part of the claimed design.

1 Claim, 9 Drawing Sheets
